JOHN C. DARNALL, OF STAUNTON, VIRGINIA.

STERILIZER.

1,217,113.

Specification of Letters Patent.

Patented Feb. 20, 1917.

Application filed April 23, 1915. Serial No. 23,514.

To all whom it may concern:

Be it known that I, JOHN C. DARNALL, a citizen of the United States of America, and a resident of Staunton, in the county of 5 Augusta and State of Virginia, have invented a certain new and useful Improvement in Sterilizers, of which the following is a specification.

This invention relates to sterilizing devices that are especially adapted for use in 10 hospitals, saloons, pharmacies, eating houses or hotels, and other places where it is desired to keep utensils, surgical instruments, cutlery, glass, metal and silver ware, as well 15 as articles of food, in a sanitary and healthful condition.

It relates, more particularly, to sterilizing-ovens in which steam is used that is in direct contact with the contents thereof.

20 The object of the invention is to provide a main-chamber or oven with a steam generating-chamber at its bottom that is under suitable valve-control and a steam condensing-chamber at its top that is also under valve-control, whereby the hot steam is liberated from the generating-chamber into the oven from below and duly liberated or released into the said condensing-chamber when the contents of the oven are to be withdrawn and without inconvenience and danger of burning or scalding to the operator of the device, the details of structure and operation being hereinafter fully described and particularly pointed out in the claims.

35 In the accompanying sheet of drawings:—

Figure 1 is a longitudinal section of the device taken on the dotted-line *b*, *b*; of Fig. 3, showing the device in normal condition ready to be prepared for use, one glass-tumbler rack being shown in supported condition in one compartment of the two of the oven and an empty tray being shown in the upper part of the other compartment.

40 Fig. 2, a front elevation of the device seen in Fig. 1 but with one of the front doors closed and the other door (to the right) open and without any trays or racks therein;

Fig. 3, an elevation of the right-hand end 50 of the device seen in Fig. 2, but with the doors closed;

Fig. 4, a vertical sectional elevation taken on the dotted-line *a*, *a*, of Fig. 2 and showing the right-hand compartment of the oven, 55 with the door closed;

Fig. 5, a detail perspective view of one form of wire-mesh tray adapted for use in the oven;

Fig. 6, a view similar to Fig. 5 but showing a tray having solid sides and ~~with~~ a 60 wire-mesh bottom;

Fig. 7, a plan view of the preferred form of rack or grating used for receiving and holding glass-ware and the like; and—

Fig. 8, a detail, fragmentary plan view of 65 the fore-end of the condensing-chamber with the top plate thereof removed so as to more clearly show the sloped corners that serve to direct the flow of the water of condensation into the drain-pipe. 70

The main-chamber or oven proper 1 of the device is preferably of rectangular shape and has a multiple of compartments in which the objects to be sterilized or treated are to be placed. 75

In Fig. 1, I have plainly shown the device as having a pair of compartments A and B placed side by side with a hollow or double-walled partition C between them, such partition having its said walls duly spaced apart to provide an insulating air-chamber.

Angular supporting-strips 2 are suitably mounted on the walls of the partition C so that they have horizontal portions extending laterally into the chambers A and B, and similar angular strips 3 are mounted on the opposite end walls so that they horizontally align with strips 2 and project laterally toward the said strips 2, both sets of strips 90 2 and 3 being respectively adapted to support trays 4 and racks 5 in the several compartments, as best shown in Fig. 1, and duly elevated at intervals apart above the bottom D of the oven. 95

Angular strips 6 are used in connection with the strips 3 to vertically align with the vertical side-edges 7 (see Fig. 2) of the door opening so that the trays or racks can be readily guided to and from place within the 100 oven through the door-ways and without undue obstruction.

E indicates a generating-chamber that forms a hollow bottom for the oven, as best shown, in Figs. 1 and 4. This chamber is 105 adapted to contain water or other fluid that is subjected to heat from below and duly converted into steam or like highly-heated gas. It is obvious that the device may be placed on a burner or stove using alcohol, 110

oil, gas or other fuel for heating the water to generate steam or otherwise vaporize it into condition for sterilizing purposes in the oven which may contain one or more compartments as desired.

5 A vertical sight-feed water-glass 8 is used at one end of the steam generating-chamber E, with its lower end elbowed and entering the lower portion or bottom of said chamber 10 E, at the right-hand end thereof, whereby said chamber E may be duly supplied with water and, also, its depth in the chamber duly indicated from without. The upper end of this water-glass is elevated somewhat 15 above the chamber E so that the water will not ordinarily escape therefrom, unless said chamber becomes overfull, and it is obvious that this glass will be useful in permitting the escape of steam to cause a hissing sound 20 of alarm in the event the water becomes too low in the chamber E whereby said steam can escape through the lower elbowed-end of the glass.

A steam outlet-opening is made in the bottom D of each of the compartments A and B, of the oven to permit the liberation of steam or gas from the chamber E into said several compartments of the oven, either both at once or independently, as desired, 30 and suitable valves 10 are provided to close said openings 9 until it is desired to liberate the steam into the oven for sterilizing purposes. These valves 10 are preferably made of a flexible fibrous material or the like that 35 is practically steam-proof and adapts itself to properly close the openings 9, and they are pivotally mounted or hinged at 11 so as to turn or be rotated backwardly away from closing-engagement, suitable weights 12 being used thereon to hold them in closed-position as well as in opened-position and, also, to allow the valves to be thrown open automatically when the pressure in the chamber E becomes greater than it should be 40 or than necessary. Handles 13 are used on the outer ends of the hinging-stems of the valves for operating them from the outside. The valves 10 taper or bevel so as to fit within the openings 9 and provide a better 45 closure. The weights 12 are correspondingly countersunk to fit within the countersunk tops of said valves 10.

14 indicates each one of the two doors of the main-chamber or oven, the same being 50 duly hinged at 15 along their outsides edges, as best shown in Fig. 2, whereby access to the oven is readily effected, and pivotal hasp-bars 16 are used in connection with a central, vertical hook or keeper 17 to 55 hold said doors tightly closed against the escape of steam. The free ends of the hasp-bars 16 approach each other, but do not contact, in the upwardly-disposed hook or keeper 17 and provide a convenient and effective fastening means.

F indicates a condensing-chamber 60 surmounting the oven 1, preferably spaced above the oven and having conductor-pipe connections 18 with the top-plate of the oven to allow the escape of steam from the oven 70 thereinto when desired. The conductor-pipe 18 is of an area of at least twice greater in steam-carrying capacity than that of the steam-opening 9 below that leads from the generating-chamber into the oven, whereby 75 said steam can more readily pass into the condensing-chamber from the oven when the valve 10 below has been closed and it is desired to open one of the oven doors for access to the contents under sterilization. This 80 is an important feature in connection with the invention herein for the reason that it enables the person to safely handle the contents of the oven without danger of the hot blistering steam escaping forwardly from 85 the oven, such steam taking the more direct course or circulation upward through the conductor-pipe into the condensing-chamber F wherein it is soon converted into water 90 and prevented from passing off or circulating into the atmosphere surrounding the device. The condensing-chamber is preferably arranged at an inclination toward the right-hand end of the device, as best shown in Figs. 1 and 2, whereby the water of condensation can more readily and quickly 95 drain or pass downward into the vertical, external drain-pipe 19 that extends from the bottom of the right outer-end of the chamber F to a level with the bottom of the generating-chamber E, as best shown in Figs. 3 and 4, where it discharges into said generating-chamber for repeated use. To further facilitate the drainage of the water 100 into the vertical tube 19 I insert sloping partitions or blocks 20 in the corners of the right-hand end of the condensing-chamber F, as shown in Figs. 1, 4 and 8, the latter view best showing that feature.

Suitable valves 21, similar to those 10 below, are provided in the condensing-chamber F so as to close the steam-exits 18. These valves 21 are of the same material as those 10 below and are similarly pivoted or hinged at 22 and have weights 23 whereby 110 they are held down to place in closing the openings 18 or away from place on the bottom of the chamber F when swung backwardly away from said openings 18 by means of the outer handles 24 when it is 115 desired to allow the escape of the steam from the oven into said chamber F at any desired time and especially when either door is open for access to the oven. The valves 21 are made tapered and the weights 120 23 countersunk in the tops thereof, the same as those 10 referred to above.

The spacing of the chamber F above the oven prevents the heating of said chamber F to a greater or less degree and thus facili- 130

tates the condensation of the steam, such space allowing cool air to circulate therein to keep the bottom of the chamber F cool as well as the conductor-pipe 18. It is obvious, of course, that the condensing-chamber 5 can be applied direct to the top of the oven without the air-space intervening, but an intermediate insulating material must be used between the oven and the chamber F to prevent the transmission of heat into 10 said chamber F that would interfere with the rapid condensation of the steam.

A pet-cock 25 is provided at the upper left-hand end of the condensing-chamber F to permit a preliminary drawing off of cool 15 air or pressure from the device when it is about to be heated for use and, under such circumstances, the upper valves 21 are thrown open for a moment or two and then said pet-cock is closed, as well as said valves 21, so that the heating of the oven, with its 20 contents therein, immediately follows thereafter.

A draw-off cock 26 is provided in the 25 bottom of the right-hand end of the generating-chamber for discharging the water therefrom when it becomes foul or should there be any sediment or the like in the chamber, or as desired.

The tray 4 shown in Fig. 6 has plain 30 solid sides and a wire-mesh or grated bottom to contain dishes or the like, and the tray 4^a shown in Fig. 5 is entirely of wire-mesh or grating construction and is especially adapted 35 to contain cutlery or surgical instruments that require special sterilization and that permits a free circulation of the steam or gases with the chance of any lodgment of germs at any place therein reduced to a 40 minimum.

The rack or grated-tray 5 shown in Fig. 7 is especially adapted for use in connection with glass-tumblers used at soda-fountains and in saloons, as it is composed of 45 narrow bars of metal 5^a that cross each other at right-angles and are duly riveted together at 5^b, the bars being bent into V-shape as shown at 5^c so as to form skeleton crowns or supports for the glasses or 50 tumblers that are placed in inverted-position thereon, as shown in Fig. 1. The glasses or tumblers being round or circular and the bars 5^a being flat, the points of supporting-contact are so slight that no 55 germs can lodge between them and the sterilization of said glasses is perfected through said grated crowns into and around said glasses, with a free circulation of the steam at all times.

In operating the device it is placed on 60 any suitable heating medium and, when the water in the generating-chamber E has become sufficiently hot to produce the required degree of steam or gas, the valves 10 are 65 thrown open and the valves 21 thrown

closed, the pet-cock 25 being, of course, first used to liberate such cool air or pressure as is present in the device before the valves 21 are closed. The trays or racks containing the objects to be sterilized are, of course, 70 first placed within the oven, in one or both compartments as desired, and the doors tightly closed. In due time, after the required sterilization has been effected, the lower valves 10 are closed and the upper 75 valves 21 opened to liberate the hot steam into the cooling and condensing chamber, from whence the water of condensation passes downwardly through the external drain-pipe 19 to the steam generating-chamber for re-use; then the front-doors 80 can be opened without danger of the steam rushing forwardly to inconvenience or burn the person who is about to remove the objects from within, whereby safety and comfort are both provided for in the use of the device that makes it practical and effective. To further render the oven safe against outward escape of the steam, an inwardly-turned lip or flange 28 is provided at the 85 top, and a slanting flange 29 is provided at the bottom, as well as similar flanges 30 are provided along the sides of the door-ways, as shown in Fig. 4, to block or retard the 90 outward rush or escape of steam and are 95 important factors in the use of my invention herein. The lower flange 29 preferably slopes downwardly so that any water of condensation can readily drop or flow from its inner edge and thus not form or allow any collection of beads on the bottom thereof.

Instead of using the oven for sterilizing purposes it is obvious that it can be employed for cooking foods, both liquid and 100 solid ones and wherein a boiling of them is preferred. It can also be used to keep foods hot ready to serve.

I claim:

1. In a sterilizer for drinking-glasses and the like, the combination with a steam sterilizing chamber arranged to receive the articles to be sterilized and provided with a closure for the introduction and removal of 110 such articles, of a condensing chamber located above said sterilizing chamber and communicating therewith by an enlarged conduit, and a valve to control said conduit, said condensing chamber being of a capacity 115 such that when the valve is opened it will receive and condense substantially all of the steam in said sterilizing chamber, whereby the closure may be opened to permit access 120 to the contained articles without discharge of steam therefrom.

2. In a sterilizer for drinking-glasses and the like, the combination with a steam sterilizing chamber arranged to receive the articles to be sterilized and provided with a closure for the introduction and removal of 125

such articles, of a steam condensing chamber located above said sterilizing chamber and communicating therewith by an enlarged conduit, a valve to control said conduit, said condensing chamber being of a capacity such that when the valve is opened it will receive and condense substantially all of the steam in said sterilizing chamber, whereby the closure may be opened to permit access to the contained articles without discharge of steam therefrom, a steam generating chamber located below the level of the condensing chamber, and a conduit leading from the condensing chamber to the generating chamber and adapted to convey condensation from the condensing chamber to the generating chamber.

3. In a sterilizer, the combination with a chamber arranged to receive the articles to be sterilized and provided with closures permitting free access to the interior of the chamber, means for supplying sterilizing vapor to said chamber and means provided to receive said sterilizing vapor preliminary to the opening of the closure whereby said chamber may be opened freely without the

objectionable discharge of sterilizing vapor through said closures.

4. In a sterilizer, the combination with a steam sterilizing chamber arranged to receive the articles to be sterilized and provided with a closure for the introduction and removal of such articles, of a condensing chamber communicating with the sterilizing chamber; a valve to control said communicating means; a steam generator; a valve to control the admission of steam from the generator into the sterilizing chamber, so arranged and connected up that when the valve controlling the entrance of steam is closed and the valve controlling the emission of steam to the condensing chamber is open, the steam in the sterilizing chamber will be discharged into the condensing chamber, whereby the closure may be opened to permit access to the contained articles without discharge of steam therethrough.

JOHN C. DARNALL.
